(57) **CLAIM**

The ornamental design for a waist trainer garment, as shown and described.

DESCRIPTION

FIG. 1 is a front view of a waist trainer garment, showing the new design;

FIG. 2 is a left view thereof;

FIG. 3 is a right view thereof;

FIG. 4 is a top view thereof;

FIG. 5 is a bottom view thereof;

FIG. 6 is a rear view thereof;

FIG. 7 is a front perspective view thereof;

FIG. 8 is a bottom perspective view thereof;

FIG. 9 is top perspective view thereof, showing a flap of the garment being partially opened; and,

FIG. 10 is bottom perspective view thereof, showing the flap of the garment being partially opened.

The broken lines depict features of the waist trainer garment that form no part of the claimed design.

1 Claim, 10 Drawing Sheets
